MULTIPLE VALVE

Application filed October 10, 1927. Serial No. 225,104.

Where protection against fire is to be afforded a given room or space, it frequently is desirable to provide detecting apparatus which enables the protective system to be brought into play as soon as the presence of fire is discovered. The protective system is usually tied in with the detecting apparatus and care must be exercised not to allow the fire extinguishing medium to be carried from the protected space to the sensitive detecting apparatus. Heretofore, separate valves have been used to permit delivery of the fire extinguishing medium and to prevent the detecting apparatus from being exposed to the extinguishing medium and their operation has been effected in successive stages to meet the above requirements. Valves have been designed which are adapted to open the fire extinguishing line and close the detecting line simultaneously in order that the proper protection may be afforded the detecting apparatus, but there still exists the possibility of failure to close the detecting line completely before opening the fire extinguishing line.

The present invention relates to valves of this character wherein the two operations are effected simultaneously and more particularly deals with mechanism which is designed to close one fluid path completely and subsequently open another, the two stages being effected in a single operation.

An object of the invention is to provide a valve of the above type which positively prevents the opening of one line before the complete closure of the second line is effected.

Other objects will appear as the description proceeds in connection with the accompanying drawings wherein:

Figure 1 is a view in section, showing the assembled valve structure with the gas valve seated and the air valve unseated.

Figure 2 is a view in section, showing both valves seated.

Figure 3 is a view in section, showing the gas valve unseated and the air valve seated.

Referring particularly to Figure 1, *a* indicates the main valve body provided with a bonnet *b*. Flanges *a'* and *b'*, upon body *a* and bonnet *b* respectively, are secured to-

gether by means of bolts *c*. Juxtaposed circumferential recesses *a²* and *b²* in the flanges *a'* and *b'*, respectively, are provided to receive a removable valve seat *d*, described more specifically hereinafter. This valve seat serves to prevent the fire extinguishing medium or gas, which is admitted through a port *a¹²* in the bonnet *b*, from entering the main body of the valve when the gas valve engages thereagainst.

At the head of the valve body *a*, a seat *a³* is formed about a passage *a⁴* which permits the interior of the valve body *a* to communicate with a chamber *a⁵* provided with a port *a⁶* to which is connected the smoke detecting apparatus. A port *a⁷* provides communication between the interior of the valve body *a* and the room which is to be protected from fire by admission of the fire extinguishing medium or gas.

A valve stem *e*, provided with a hand wheel *e'*, extends within the valve body and has pinned to it threaded bushings *e²* and *e³*, the former engaging threads *a⁸* in the head of the valve body *a*, and the latter engaging a threaded bushing *f*. A suitable cap *a⁹* may be threaded over the end of the valve body in a well known manner, and a washer *a¹⁰* is secured to the end of the valve stem by means of nuts *a¹¹*.

The removable seat *d* is provided with upwardly extending arms *d'* provided with flat surfaces *d²*. These flat surfaces are engaged by flat surfaces *f'* upon the movable bushing *f* and serve to prevent rotation of the bushing while it is permitted to move in an axial direction. The bushings *e²* and *e³* are provided with threads having the same direction of rotation and the lead of the thread on bushing *e³* is twice that of the thread on the bushing *e²*, that is, the bushing *e³* has a so-called double thread and bushing *e²* a single tread. If the hand wheel *e'* is rotated in the proper direction, the valve stem *e* will advance toward the left into the valve body, and since the lead of the thread on the bushing *e³* is twice that of the thread on the bushing *e²*, the bushing *f* will travel along the valve stem *e* twice as far as the valve stem enters the thread which engages the

bushing e^2 . As the valve stem is not stationary, but advances toward the left, the bushing f will not move twice as far, with respect to the valve body a , as the valve stem moves toward the left. The result is that the bushing f moves just as far to the right, with respect to the valve body a , as the valve stem e , together with bushing e^2 , moves toward the left.

10 A suitable valve bonnet g is loosely carried upon the bushing f by means of a circumferential flange f^2 . This bonnet g carries a valve body g' provided with a valve disc g^2 , and a valve spring g^3 , engaging the bushing f , urges the valve body g' to the right. A second bonnet h carries a valve body h' , which is provided with a valve disc h^2 . A spring h^3 normally urges the valve body h' to the right and causes it to engage the removable seat d . This closing action, of course, supplements the closing force normally exerted by the valve stem e through nuts a^{10} and a^{11} upon valve body h' . The valve structure last described controls the flow of extinguishing medium from the supply port a^{12} in the valve bonnet b , through the valve body a and out the port a^7 .

The operation of the device is as follows: In its normal position the gas valve h , h' , h^2 , 30 is tight against the seat d and the air valve g , g' , g^2 is open. This condition is shown in Figure 1. As the valve stem e is advanced into the valve body, the bushing f moves to the right, causing the air valve to engage the seat a^3 . As the valve is seated, the spring g^3 is compressed to cause it to seat tightly. This condition is illustrated in Figure 2. In the continued movement of the valve stem, the bushing e^3 , moving to the left with the valve 40 stem, finally engages the valve disc h^2 which is maintained in a seated position by means of spring h^3 . Continued movement of the valve stem e unseats this gas valve and permits the flow of the medium through the port a^7 . Figure 3 illustrates this position of the 45 valve. The parts are designed to provide for sufficient lost motion between the bushing e^3 and the valve h^2 to enable the valve disc g^2 to engage the seat a^3 tightly before the valve disc h^2 is moved from the seat d . It will be seen, therefore, that this structure 55 positively closes the valve which communicates with the detecting mechanism before the gas valve is opened to introduce the fire extinguishing medium into the chamber with which the detecting mechanism communicates. In connection with the operation defined above, it will be apparent that the force of the spring h^3 is supplemented by the force exerted by the extinguishing medium within the valve bonnet b . It would be possible to dispense with the valve spring h^3 and utilize the pressure of the extinguishing medium to exert the necessary closing force upon the valve body h' . In connection with the

operation defined above it will be apparent that, in the reverse operation, the gas valve is closed before the air valve opens.

No limitation upon the scope of this invention is to be imposed by reason of the above 70 description, since the elements can be rearranged and designed to meet various needs.

I claim as my invention:

1. A valve comprising a valve body having a plurality of ports, separate valves for controlling the fluid flow through the ports, a unitary valve stem carried in the valve body for mounting the valves and means operated by the stem to cause one of the valves to be operated more rapidly than another to effect 80 the closure thereof and place one of the ports in communication with another port to the exclusion of a third.

2. A valve comprising a valve body having a plurality of ports, separate valves for controlling the fluid flow through the ports, a valve stem carried in the valve body, a bushing secured to the stem and engaging the valve body to cause the stem to be moved axially when rotated, a second bushing, means 85 to operate one of the valves from the second bushing and means to operate another of the valves after a predetermined movement of the stem.

3. A valve comprising a valve body having a plurality of ports, separate valves for controlling the fluid flow through the ports, a valve stem carried in the valve body, a bushing secured to the stem and engaging the valve body to cause the stem to be moved 95 axially when rotated, a second bushing, and means to operate one of the valves from the second bushing, said second bushing operating another of the valves after a predetermined movement of the stem.

4. A valve comprising a valve body having a plurality of ports, separate valves for controlling the fluid flow through the ports, a valve stem carried in the valve body, a bushing secured to the stem and engaging the 100 valve body to cause the stem to be moved axially when rotated, a second bushing, means to operate one of the valves from the second bushing and means to operate another of the valves after the first valve has been seated.

5. A valve comprising a valve body having a plurality of ports, separate valves for controlling the fluid flow through the ports, a valve stem carried in the valve body, a bushing secured to the stem and engaging the valve body to cause the stem to be moved 110 axially when rotated, a second bushing, means to cause one of the valves to be closed and urged under a yielding pressure against its seat and means to open another of the valves 115 after the closing pressure of the first valve has reached a predetermined amount.

6. A valve comprising a valve body having a plurality of ports, separate valves for controlling the fluid flow through the ports, a 120

- valve stem carried in the valve body, a bushing secured to the stem and engaging the valve body to cause the stem to be moved axially when rotated, a second bushing secured to the stem, and a bushing operated by the second bushing to close one of the valves, said second bushing opening another of the valves after the first valve has been closed. 5
7. A valve comprising a valve body having a plurality of ports, separate valves for controlling the fluid flow through the ports, a valve stem carried in the valve body, a bushing secured to the stem and engaging the valve body to cause the stem to be moved axially when rotated, a second bushing secured to the stem, a bushing operated by the second bushing to close one of the valves, and means to move the last bushing in an opposite direction to the valve stem to close one 10 of the valves, said second bushing opening another of the valves after the first valve has been closed.
8. A valve comprising a valve body having a plurality of ports, separate valves for controlling the fluid flow through the ports, a valve stem carried in the valve body, a bushing secured to the stem and engaging the valve body to cause the stem to be moved axially when rotated, a second bushing secured to the stem, a bushing operated by the second bushing to close one of the valves, and means to move the last bushing in an opposite direction to the valve stem with a speed equal thereto to close one of the valves, said 15 second bushing opening another of the valves after the first valve has been closed.
9. A valve comprising a valve body having a plurality of ports, separate valves for controlling the fluid flow through the ports, a valve stem carried in the valve body, a bushing secured to the stem and engaging the valve body to cause the stem to be moved axially when rotated, a second bushing secured to the stem, a bushing threaded upon the second bushing, flat surfaces on the last bushing, a removable seat carried by the casing, flat surfaces formed on the removable seat and engaged by the flat surfaces on the bushing to constrain the latter to axial movements, and means operated by the last bushing to close one of the valves, said second bushing opening another of the valves after the first 20 valve has been closed. 40
10. A valve comprising a valve body having a plurality of ports, separate valves for controlling the fluid flow through the ports, a valve stem carried in the valve body, a bushing secured to the stem and engaging the valve body to cause the stem to be moved axially when rotated, a second bushing secured to the stem, a bushing, a double thread mounting the latter upon the second bushing, flat surfaces on the last bushing, flat surfaces carried by the valve body and engaged by the flat surfaces on the bushing to constrain the latter to axial movements, and means op- 25
- erated by the last bushing to close one of the valves, said second bushing opening another of the valves after the first valve has been closed. 5
11. A valve comprising a valve body having a plurality of ports, separate valves for controlling the fluid flow through the ports, a valve stem carried in the valve body, a bushing secured to the stem and engaging the valve body to cause the stem to be moved axially when rotated, a second bushing secured to the stem, a valve bonnet engaged by the last bushing, a valve operated by the bonnet, a spring engaging the last bushing and urging the valve upon its seat, said second bushing opening another of the valves after the first valve is closed, and a spring to resist the operation of the second valve by the second bushing. 70
12. A valve comprising a valve body having a plurality of ports, separate valves for controlling the fluid flow through the ports, a removable seat carried by the valve body, a single means to cause one of the valves to disengage the seat and to operate another of the valves, and means carried by the seat cooperating with the last named means to effect the operation thereof. 80
13. A valve comprising a valve body having a plurality of ports, separate valves for controlling the fluid flow through the ports, a valve stem carried in the valve body, a bushing secured to the stem and engaging the valve body to cause the stem to be moved axially when rotated, a second bushing secured to the stem, a bushing threaded upon the second bushing, flat surfaces on the last bushing, a removable seat carried by the casing, flat surfaces formed on the removable seat and engaged by the flat surfaces on the bushing to constrain the latter to axial movements, and means operated by the last bushing to close one of the valves, said second bushing opening another of the valves after the first valve has been closed. 100
14. A valve comprising a valve body, a bonnet therefor, a port in the bonnet, ports in the body, a valve controlling the communication between the last two ports, a removable seat carried between the body and the bonnet, a valve engaging the removable seat, means to cause one of the valves to be unseated after the other has been seated, and means carried by the seat cooperating with the last named means to effect the operation thereof. 115
